UNITED STATES PATENT OFFICE

147,414

DESIGN FOR A KITCHEN TABLE

Harold B. Maynard, Pittsburgh, and Charles W. Punton, Wilkinsburg, Pa., assignors, by mesne assignments, to Haskell Manufacturing Company, a corporation of Pennsylvania

Application April 4, 1946, Serial No. 128,291

Term of patent 14 years

(Cl. D33—14)

To all whom it may concern:

Be it known that we, Harold B. Maynard and Charles W. Punton, citizens of the United States, residing, respectively, at Pittsburgh and R. D. 1, Wilkinsburg, both in the county of Allegheny and State of Pennsylvania, have invented a new, original, and ornamental Design for Kitchen Table, of which the following is a specification, reference being had to the accompanying drawings, forming part thereof.

In the drawings:

Fig. 1 is a front view of a table showing our new design;

Fig. 2 is an end view thereof; and

Fig. 3 is a perspective view of the table as it appears when its top is in elevated position.

We claim:

The ornamental design for a kitchen table, as shown.

HAROLD B. MAYNARD.
CHARLES W. PUNTON.
